UNITED STATES PATENT OFFICE

JOHN WICKS, OF OAK PARK, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TESTING APPARATUS

Application filed September 29, 1930. Serial No. 484,944.

This invention relates to testing arrangements in general, particularly to testing arrangements for use in automatic telephone systems and is concerned primarily with improved apparatus and circuits for extending a connection from a test switchboard to a subscriber's line terminating in an automatic exchange.

In systems of the above type routine tests on subscribers' lines are ordinarily made at a central test switchboard or wire chief's test desk. Special test trunks extend from the switchboard to each exchange in the system, and each exchange is provided with a special test switch train for extending connections to the subscriber's line. A clear metallic circuit free of bridges and other connections is required for testing purposes. This is the main reason for providing the special test switch train, as the regular exchange switching apparatus ordinarily used is not adapted to provide such a circuit.

Testing systems have been proposed in which test connections are extended, in part, over the exchange switching apparatus. Heretofore systems of this type have required changes and modifications in the exchange switching apparatus in order to provide a circuit that is suitable for testing purposes. Such arrangements are objectionable due to the increased cost and to the added difficulties in maintaining the more complicated equipment.

An object of the present invention is the provision of an improved arrangement whereby test connections may be extended in part over exchange switching apparatus such as is ordinarily provided for local and toll service without requiring any changes or modifications whatever in such apparatus. This object is attained by providing a simple test selector adapted to operate with the standard test switchboard circuits, the selector being grouped with the regular battery feeding selectors of the exchange and having access in

common with these switches to the intermediate selectors and connectors of the exchange.

The various features of the invention will be described in detail in connection with the description of the operation of the various circuits involved, reference being had to the accompanying single figure of drawing. In the drawing there is shown by means of the usual circuit diagrams, the embodiment of the invention in a telephone system in which talking battery is fed from a selector in both local and toll connections. A telephone system of this type is disclosed in the co-pending application of Wicks, Serial No. 395,882, filed September 28, 1929. It will be appreciated that the invention may be employed equally well to systems in which talking battery is fed from the connector in local connections and from a selector in toll connections, such for example as the system disclosed in United States Patent No. 1,786,041, granted Dec. 23, 1930 to Tharp and Wicks.

Referring now to the drawing, test cord TC, of which only a part is shown, may be similar to the test cord disclosed in United States Patent No. 1,691,269 to Crocker, of November 13, 1928. The cord circuit is associated with the usual testing devices, indicated in the drawing by a dotted line, and is adapted to connect with test trunks, such as the one extending from the manual jack J to test selector TS. Trunk relays TR are associated with the trunk line and are located at the switchboard end of the trunk. The trunk line which comprises four conductors extends from the trunk relay group to test selector TS, which incidentally may be located in the same office as the test desk or in a different office. The test selector together with local selector repeaters, such as the selector repeater SR, and toll transmission selectors, such as the selector TTS, have access to intermediate selectors of which one, namely, selector IS is shown. The inter-

mediate selectors in turn have access to the various connectors of the system, such as connector C which has access to different subscribers' lines including that extending to 5 substation T. It will be noted that the test selector is arranged to connect with the intermediate selector trunks in the same manner as the toll selector, that is, the upper wiper of the test selector connects with the 10 upper trunk conductor whereas in the case of the local selector repeater the upper wiper connects with the lower trunk conductor. The purpose of this arrangement will be explained in later paragraphs. The selector 15 repeater, toll transmission selector, intermediate selector and connector have been shown only in skeleton form since these switches may be exactly the same as the corresponding switches shown in the previously 20 referred to Wicks application, Serial No. 395,882.

By way of illustration the operations involved in extending a connection from the test switchboard to the subscriber's line terminating in substation T will now be described. Plug P, of the test cord TC is inserted in the jack of an idle trunk for example, jack J, whereon contacts 27 close and complete a circuit for relay 4. Relay 4, operates, closes a point in the control circuit at contacts 21 and prepares a holding circuit for itself in series with relay 3 at contacts 20. Relay 1 of the trunk circuit operates over a circuit extending by way of the sleeve of the 25 jack and plug, resistance 6, to ground at contacts 26. Relay 1 on operating completes a loop circuit for operating relay 33 of the test selector by closing contacts 10, and by opening contacts 7 and 11 and closing contacts 8 and 12, the tip and ring springs of the jack are disconnected from the control conductors and connected to the test conductors of the 30 trunk. Referring now to test selector, relay 33 operates over the previously described 35 loop which includes contacts 21 and conductors 29 and 32, completes a circuit from ground at contacts 55, winding of relay 34, windings of relay 35 to battery, and in parallel therewith through release magnet 40 contacts, contacts 79, winding of vertical magnet 40, to battery. Relay 33 also closes a 40 circuit for relay 36 by way of contacts 52, 66 and 74, resistance 48, to ground. Relay 34 operates, but due to its relatively high resistance neither the vertical magnet nor relay 35 operate at this time. Relay 34 connects ground to the local holding circuit at 45 contacts 56, prepares the impulsing circuit at contacts 57, and opens the release magnet circuit at contacts 58. Relay 36 now operates and opens a point in the circuit of relay 37 at contacts 62.

The foregoing operations take place responsive to the insertion of the plug of a test cord into the jack of an idle trunk line. The

wire chief will now dial the first digit of the number designating the wanted line. When the calling device CD is turned off-normal, contacts 14 close and complete a circuit for relay 5. Relay 5, operates, disconnects the 50 ring and tip conductors of the cord circuit from the testing apparatus and connects them to the impulse contacts of the dial at contacts 23 and 25, and at contacts 26 disconnects ground from the sleeve of the plug. Relay 1 of the trunk circuit restores due to the removal of ground from the sleeve and switches control conductors 29 and 32 of the trunk through to the tip and ring springs of the jack. Relay 33 of the test selector is now 55 held operated over a control loop which includes the impulsing contacts 15 of the calling device. Calling device CD on returning to normal interrupts the loop circuit at contacts 15 in accordance with the number dialled, and relay 33 responds accordingly by deenergizing and reenergizing. Each time relay 32 deenergizes a circuit is closed from ground at contacts 57, contacts 54, through the windings of relay 35 to battery, and by way of the release magnet contacts and contacts 79, through the winding of vertical magnet 40 to battery. Both the relay and the magnet operate under these conditions and the wipers of the selector are raised 60 one step. Relay 34 is slow to release due to its winding being short circuited at contacts 54 and remains operated during impulsing. Relay 35 also remains energized throughout 65 series of impulses being slow-to-release, due to its series connection with relay 34. At the end of the series of impulses contacts 14 of the calling device will again open and relay 5 will restore thereby reconnecting the 70 test apparatus to the ring and tip conductors of the cord. Ground on the sleeve reoperates relay 1 and the holding loop for relay 33 is again closed at contacts 10. In the test selector, relay 35 restores shortly after the 75 last impulse of the series and, since off-normal contacts 44 have closed on the first vertical step of the wipers, a circuit is completed for rotary magnet 41 by way of contacts 61 and 77 and interrupter contacts 81. Magnet 41, energizes, rotates the wipers one 80 step and interrupts its own circuit at contacts 81. This operation will be repeated until test wiper 84 encounters an idle trunk, which is marked by the presence of battery potential on the test conductor corresponding to conductor 88. When an idle trunk is encountered relay 39 will operate over its upper winding and open the circuit of the rotary magnet at contacts 77, thereby stopping the rotary movement of the wipers. Relay 39 completes a locking circuit for its 85 lower winding in series with the rotary magnet by closing contacts 76, and short-circuits its upper winding at contacts 75 to mark the seized trunk line busy by connecting direct 90 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 95 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 100 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 105 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 110 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 115 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 120 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 125 to conductor 88. When an idle trunk is encountered relay 39 will operate over its upper winding and open the circuit of the rotary magnet at contacts 77, thereby stopping the rotary movement of the wipers. Relay 39 completes a locking circuit for its lower winding in series with the rotary magnet by closing contacts 76, and short-circuits its upper winding at contacts 75 to mark the seized trunk line busy by connecting direct 130 to conductor 88.

ground thereto. It will be recalled that relay 36 was energized when the switch was seized. During the transmission of each series of impulses a temporary holding circuit for the relay is completed by way of contacts 53, resistance 50, and contacts 56. Upon the operation of relay 39 the line wipers 82 and 85 are connected to the control conductors of the switch and the original energizing circuit of relay 36 is opened at contacts 74. Relay 36 remains energized, however, over a circuit which may be traced from battery, winding of the relay, contacts 52, 66 and 73, wiper 82, trunk conductor 86, through the winding of the impulse relay of the intermediate selector IS, trunk conductor 89, wiper 85, contacts 80 and 69, to ground. The impulse relay of the intermediate selector energizes in series with relay 36 and prepares the selector for operation.

The wire chief will now dial the next digit of the number whereon the switching operations in the cord and trunk circuits take place as for the previous digit. Impulse relay 33 of the test selector responds as before and with each deenergization interrupts the loop circuit for the impulse relay of the intermediate selector at contacts 52. Relay 35 again operates during the series of impulses but has no effect at this time. It will be noted, however, that the upper winding of relay 35 is now short-circuited by way of contacts 78 and the release magnet contacts. This is for the purpose of increasing current flow in the circuit of release relay 34 to insure the complete energization of that relay. The impulse relay of the intermediate selector responds to the impulses in the usual way and the wipers of the switch are raised to the called level whereon they are rotated over the bank in search of an idle trunk. It will be assumed, for convenience, that the trunk comprising conductors 90-93 terminating in connector C is the one selected. Selector IS on seizing this trunk disconnects the control loop from the impulse relay of the selector and extends it over conductors 90 and 93 to the impulse relay of connector C which operates.

It was previously mentioned that the upper wiper of test selector TS connected with the upper trunk conductor whereas the upper wiper of a local selector repeater, such as SR, connected with the lower talking conductor of the trunk. In both selectors, battery is connected to the upper wiper and ground to the lower wiper so that battery flow over the connection will be in one direction in local calls and in the opposite direction in test calls. This arrangement is for the purpose of operating a polarized relay which is connected in series with the impulse relay of the connector. This polarized relay on operating prepares the connector for toll operation by preparing the special test circuit and by lock-

ing up the ring-cut-off relay of the connector to prevent ringing current from being applied to the called line.

The second and third digits are now dialled. The test selector repeats these series of impulses in the same manner as in the case of the second series of impulses, and the wipers of connector C are operated into engagement with the contacts associated with the wanted subscriber's line, that is, the line comprising conductors 94-96.

It will be assumed first that the called line is idle at this time and that the connector cuts in and seizes the line in the usual way. When the line is seized, the impulse relay of the connector is disconnected from the control loop and loop is extended through to the wipers of the connector. It will be recalled that relay 36 of the test selector has been held operated throughout the setting of the switches, first, over a local circuit, second, in series with the impulse relay of the intermediate selector, and last, in series with the impulse relay of the connector. When the connector cuts through, the opening of the control circuit permits relay 36 to release and a circuit is thereby closed at contacts 62 for relay 37. Relay 37 operates, completes a locking circuit for itself at contacts 64, and extends the control conductors of the selector through to the test conductors of the trunk at contacts 67 and 68. The intermediate selector and connector are prevented from releasing at this time by ground on the release trunk conductors applied via contacts 56 of the test selector. It will be clear from the foregoing that there is now a clear metallic circuit from the testing apparatus at the test switchboard to the subscriber's line, which circuit extends by way of contacts 22 and 24 of the cord circuit, tip and ring contacts of the plug, tip and ring springs of the jack, contacts 8 and 12, trunk conductors 30 and 31, contacts 67 and 68 of relay 37, contacts 73 and 80 of relay 39, wipers 82 and 85, trunk conductors 86 and 89, line wipers of intermediate selector IS, trunk conductors 90 and 93, line conductors of connector C, and wipers of that connector, respectively, to line conductors 94 and 96. The wire chief

may now apply the usual test to the called line over the above circuit, and if desired may signal the subscriber on the line by applying ringing current to the test circuit at the cord.

It may happen that the wire chief finds it necessary to attend to other matters and at the same time is desirous of holding up the connection previously described. In this case it is only necessary to withdraw the plug from the jack whereon contacts 27 will open and remove the short circuit from relay 3. Relay 3 will operate in series with relay 4 which remains operated, and a holding circuit is closed for impulse relay 33 of the test selector

at contacts 16. Relay 3 also prepares a supervisory circuit by connecting ground to test conductor 30 at contacts 17 and battery through relay 2 to test conductor 31 at contacts 19. Should the subscriber on the called line attempt to make a call at this time, the removal of the receiver will, of course, complete a direct current bridge whereon relay 2 will operate and complete a circuit for supervisory lamp L at contacts 13. The lamp will glow to indicate this condition to the wire chief.

When it is desired to release the connection the plug is withdrawn from the jack whereon the operations above described take place. Key K is then actuated to close contacts 28 thereby shunting relays 3 and 4 which restore. Relay 3 on restoring opens the holding loop at contacts 16 and disconnects the supervisory relay from test conductor 31. Relay 4 opens its own holding circuit at contacts 20. Relay 33 of the test selector restores and shortly thereafter relay 34 restores. A circuit is now closed by way of off-normal springs 43 which closed on the first vertical step of the wipers, contacts 58, winding of release magnet 42 to battery. The release magnet operates in the usual way to restore the switch wipers to normal position. The release of relay 34 also removes ground from the release trunk conductor at contacts 56 thereby permitting intermediate selector IS and connector C to restore in the usual way.

In the foregoing connection it was assumed that idle switches were available for extending the connection as desired. In case no idle intermediate selector is available when the test selector is operated, the rotary magnet will advance the wipers over the called level to the eleventh position, that is, beyond the last set of contacts of the bank. In this position rotary off-normal springs 51 and 45 are operated, the former connecting the usual busy tone to trunk conductor 29 to inform the wire chief that all trunks are busy. The closure of contacts 45 completes an operating circuit for relay 39 extending by way of contacts 45 and the winding of vertical magnet 40 to battery. Relay 38 operates and opens the circuit of the rotary magnet at contacts 77 and connects magnet 41 in parallel with magnet 40. It may be noted, however, that due to the relatively high resistance of relay 39, neither the rotary magnet nor the vertical magnet will operate in series with relay 39. The wire chief on noting the busy tone is expected to release the connection as previously described.

When an intermediate selector encounters an all trunks busy condition, substantially the same operations take place although in this case the busy tone is applied to the trunk from the intermediate selector. The circuit of relay 36 is opened, of course, and this relay restores and permits switch-over

relay 37 to operate thereby transferring the connection to the test conductors of the trunk so that the busy tone is transmitted thereover.

When the connector encounters a line busy in another connection the wiper closing relay of the connector will be connected in a circuit including control conductors 91 and 87, wiper 83 of the test selector, contacts 60, resistance 49, winding of relay 38 to battery. Relay 38 will operate in this circuit but due to resistance 49, the wiper closing relay of the connector does not operate at this time. Relay 38 applies busy tone to trunk conductor 29 at contacts 70 and at contacts 72 completes a locking circuit for itself. The wire chief can now effect a connection with the busy line by dialling an additional digit. Relay 33 of the test selector responds in the usual way to this additional digit and relay 35 also operates. Relay 35 on operating disconnects relay 38 from the control conductor and by way of contacts 59 and 71 connects battery via resistance 46 to the conductor instead. The value of resistance 46 is such that the wiper closing relay of the connector will operate and switch the connection through in the usual way. The impulse relay of the connector will be disconnected as usual and the switch-over operation in the test selector will take place as previously described. The line conductors are now extended over the test conductors of the trunk to the testing apparatus at the test switchboard to which the operator's telephone set may be connected as desired. The wire chief can then listen in to determine whether or not the line is busy in a connection or whether it is being held up due to a fault. If the line is engaged in another connection the wire chief may effect the release thereof by applying ground to both test conductors of the trunk. This ground operates a differential relay in the local selector repeater engaged in the connection with the busy line, this relay causing the selector repeater and other switches involved to release in a well-known manner. The wire chief can then apply the usual tests to the line after having the exchange attendant release the line switch in the usual manner.

What is claimed is:

1. In a telephone system, a test switchboard, a train of automatic switches for extending a connection from the switchboard to a subscriber's line, a feeding bridge in the first switch of the train for feeding battery in the direction of the called line, and automatic means for disconnecting said bridge and for establishing a clear metallic circuit between the switchboard and the subscriber's line.

2. In a telephone system, a test switchboard, a train of automatic switches for extending a connection from the switchboard to a subscriber's line, a feeding bridge in the

first switch of the train for feeding battery in the direction of the called line during the setting of the switches, and means responsive to the completion of the connection with the line for disconnecting said bridge and for establishing a clear metallic circuit between the switchboard and the line.

3. In a telephone system, a test switchboard, a trunk line comprising operating conductors and test conductors terminating in the switchboard, automatic switches, means controlled from the switchboard for operating said switches to establish a connection with a subscriber's line independent of said test conductors, and means responsive to the establishment of the connection with said line for including said test conductors in the connection.

4. In a telephone system, a test switchboard, a test selector, other automatic switches, means controlled from the switchboard for operating said selector and said other switches to establish a clear metallic circuit between the selector and a subscriber's line, and automatic means responsive to the establishment of a connection with the line for extending said circuit through to the switchboard.

5. In a telephone system, a test switchboard, a test selector, other automatic switches, a trunk line comprising operating conductors and test conductors extending from the switchboard to said selector, means controlled over said operating conductors for operating said selector and said other switches to complete a clear metallic circuit between the selector and a subscriber's line, and automatic means including a relay controlled by said other switches for connecting said circuit to said test conductors.

6. In a telephone system, a test switchboard, a trunk line comprising operating conductors and test conductors, a test selector and a connector, means controlled over said operating conductors for operating said selector to seize said connector, a control circuit extending from the selector to the connector, means in the selector controlled over said operating conductors for interrupting said circuit to transmit digit impulses, a relay in the connector responsive to said impulses for setting the connector on a subscriber's line, and means in the selector responsive to the connector engaging said line for extending the control circuit to the test switchboard via said test conductors.

7. In a telephone system, a test switchboard, a trunk line comprising operating conductors and test conductors, a test selector and a connector, means controlled over said operating conductors for operating said selector to seize connector, a control circuit extending from the selector to the connector, means in the selector for connecting a source of current to said circuit, means in the se-

lector controlled over said operating conductors for interrupting said circuit to transmit digit impulses over the circuit, a relay in the connector responsive to said impulses for setting the connector on a subscriber's line, and means in said selector responsive to the connector energizing said line for connecting said test conductors to said circuit in place of said current source.

8. In a telephone system, subscribers' lines, a test switchboard, means including a selector repeater and a connector for completing a talking connection between two subscribers' lines, and means including another selector repeater and said connector for completing a test connection comprising a clear metallic circuit free of bridges and branch connections from said switchboard to a subscriber's line.

9. In a telephone system, a test switchboard, a toll switchboard, means including a selector repeater and a connector for extending a talking connection from said toll switchboard to a subscriber's line, and means including another selector repeater and said connector for completing a test connection comprising a clear metallic circuit free of bridges and branch connections from said test switchboard to a subscriber's line.

10. In a telephone system, subscribers' lines, a toll switchboard, a test switchboard, means including a local selector repeater and a connector for completing a talking connection between two subscribers' lines, means including a toll selector repeater and said connector for completing a talking connection between said toll switchboard and a subscriber's line, and means including a test selector repeater and said connector for completing a test connection between said test switchboard and a subscriber's line.

11. In a telephone system, a selector repeater, a trunk line comprising operating conductors and test conductors terminating in said selector repeater, a trunk line including operating conductors accessible to said selector repeater, means controlled over the operating conductors of said first trunk line for operating said selector repeater to connect with said second trunk line and for then transmitting impulses over the operating conductors of said second trunk line to extend a connection to a subscriber's line, and means in the selector repeater for connecting the operating conductors of said second trunk line directly to the test conductors of said first trunk line.

12. In a telephone system, a selector repeater, a trunk line comprising operating conductors and test conductors terminating in said selector repeater, a trunk line including operating conductors accessible to said selector repeater, means controlled over the operating conductors of said first trunk line for operating said selector repeater to connect

- with said second trunk line and for then transmitting impulses over the operating conductors of said second trunk line to extend the same into connection with a subscriber's line, and means responsive to the establishment of said connection for connecting the operating conductors of said second trunk line directly to the test conductors of said first trunk line.
13. In a telephone system, an automatic switch, a trunk line comprising two pairs of conductors terminating in said switch, a second trunk line including a pair of conductors accessible to said switch, means controlled over one pair of conductors of said first trunk line for operating said switch to connect with said second trunk line, means in said switch for connecting a bridge across the conductors of said second trunk line and for interrupting said bridge to transmit impulses over the second trunk line whereby the second trunk line is extended into connection with a subscriber's line, and means in said switch for connecting the other pair of conductors of said first trunk line to the conductors of said second trunk line in place of said bridge.
14. In a telephone system, an automatic switch, a trunk line comprising operating conductors and test conductors terminating in said switch, a trunk line including operating conductors accessible to said switch, means controlled over the operating conductors of said first trunk line for operating said switch to connect with said second trunk line and for then transmitting impulses over the operating conductors of said second trunk line to extend a connection to a subscriber's line, means in said switch responsive when the subscriber's line is busy for applying a characteristic tone to an operating conductor of said first trunk line, and means in said switch responsive when the subscriber's line is idle for connecting the operating conductors of said second trunk line directly to the operating conductors of said first trunk line.
15. In a telephone system, a first automatic switch, a second automatic switch, a trunk line comprising operating conductors and test conductors terminating in said first switch, a trunk line including operating conductors terminating in said second switch, means controlled over the operating conductors of said first trunk for operating said first switch to establish a connection with said second switch via said second trunk line and for then transmitting impulses over the operating conductors of said second trunk line to set said second switch on a subscriber's line, and means in the first switch controlled over the operating conductors of said second trunk line for completing a direct connection between the operating conductors of said second trunk line and the test conductors of said first trunk line.
16. In a telephone system, automatic switches, a trunk line comprising two pairs of conductors terminating in one of said switches, means controlled over the first pair of conductors of said trunk line for setting said one switch, a relay in said one switch energized over a local circuit during the setting of the switch and over an external circuit extending to a succeeding switch at the completion of the operation of said one switch, means in said one switch controlled over the first pair of conductors of said trunk line for transmitting impulses over said external circuit to set said succeeding switch, means for opening said external circuit at the completion of the operation of said succeeding switch to deenergize said relay, and means responsive to the deenergization of said relay for connecting the second pair of conductors of said trunk line to said external circuit in place of said relay.
17. In a telephone system, a trunk line comprising two operating conductors and two test conductors, said operating conductors normally terminating in the springs of a manual jack at one end and in the impulse relay of an automatic switch at the other end and said test conductors being normally open at both ends, means responsive to the establishment of a connection with said trunk line via said jack, for connecting said test conductors to the jack springs in place of said operating conductors and for closing a bridge across said operating conductors to operate said impulse relay, means controlled over said jack for temporarily restoring the normal connection of said conductors to the jack springs to place said relay under control of a calling device for setting said switch, and means effective after said switch has been set for connecting said test conductors through to a subscriber's line.
18. In a telephone system, subscribers' lines, a test switchboard, selector switches, a connector switch, means for operating said switches to establish a talking connection between two subscribers' lines, means for operating a portion of said selector switches and said connector switch to establish a test connection between the switchboard and a subscriber's line, and means at the switchboard for measuring the electrical characteristics of the line over said test connection.
19. In a telephone system, subscribers' lines, a toll switchboard, a test switchboard, a train of automatic switches, means for establishing a talking connection between two subscribers' lines over said switch train, means for establishing a talking connection between the toll switchboard and a subscriber's line over a part of said switch train, and means for establishing a test connection between the test switchboard and a subscriber's line over said part of the switch train.
20. In a telephone system, a subscriber's

line, a local selector, a toll selector, a test selector, an intermediate selector, a connector, means for establishing an inductive connection to said line over said local selector, said intermediate selector and said connector, means for establishing an inductive connection to said line over said toll selector, said intermediate selector and said connector, and means for establishing a clear metallic connection to said line over said test selector, said intermediate selector and said connector.

In witness whereof, I hereunto subscribe my name this 27th day of September, A. D. 1930.
